SAWMILL OF THE CIRCULAR SAW RECIPROCATING CARRIAGE TYPE

Enno J. Dornath, Coquille, and Louis R. Detwiler,
Maupin, Oreg.

Application August 4, 1952, Serial No. 302,576

5 Claims. (Cl. 143—54)

1

This invention relates to new and useful improvements in saw mills and the primary object of the present invention is to provide a saw mill including a sliding carriage having adjustable holding means thereon whereby logs of various diameters may be attached and moved with the carriage through a sawing unit.

Another important object of the present invention is to provide a saw mill including a saw unit composed of relatively adjustable pairs of parallel blades so that various thickness of side cuts may be made in a log as a carriage, supporting the log, is moved past the sawing unit.

A further object of the present invention is to provide a saw mill that will effectively trim the bark from a log while cutting the log into square timber and which involves a means for retaining the side cuts relative to the log until the log is released from the holding means of the carriage.

A still further object of the present invention is to provide a saw mill of the aforementioned character as extremely simple and practical in construction, strong and reliable in use, efficient and durable in operation, inexpensive to manufacture, service and maintain, and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a plan view of the present invention;

Figure 2 is an enlarged fragmentary front elevational view of Figure 1;

Figure 3 is a vertical sectional view taken substantially on the plane of broken section line 3—3 of Figure 2;

Figure 4 is a vertical sectional view taken substantially on the plane of section line 4—4 of Figure 2;

Figure 5 (Sheet 3) is an enlarged detail vertical sectional view taken substantially on the plane of section line 5—5 of Figure 4;

Figure 6 is an enlarged detail vertical sectional view taken substantially on the plane of section line 6—6 of Figure 1; and

Figure 7 is an enlarged detail vertical sectional view taken substantially on the plane of section line 7—7 of Figure 5.

Referring now to the drawings in detail, wherein for the purpose of illustration there is disclosed a preferred embodiment of the present invention, the numeral 10 represents a pair of spaced parallel horizontal rails that are retained

2

in elevated position by suitable end supports (not shown) and an intermediate support 12.

A carriage 14 is movable back and forth upon the rails 10 and includes a pair of inverted U-shaped frame members 16 that are fixedly connected at their apices by a horizontal I-beam 18 whose upper flange supports a reversible electric motor 20 that is connected to a rotary member or worm 22. The member 22 is engaged with a horizontal trolley line 24 so that as the member 22 is rotated, the carriage 14 may move on its wheels 26 which are engaged upon the rails 10.

Holders 28 and 30 are slidably received on the I-beam 18. Each holder is substantially channel-shaped in cross-section to receive the lower flange of the I-beam and the leg portions of the channels are bent inwardly to overlie the lower flange of the I-beam, as shown in Figure 4. Holders 28 and 30 are connected together by a pneumatically operated jack 32 having a cylinder 34 attached to the holder 30 and a piston rod 36 attached to the holder 28.

Valve means 38 supported on the I-beam 18 and operatively connected to a source of fluid pressure and to the ends of cylinder 34 by conduits, constitutes means whereby the piston rod 36 may be selectively extended or retracted for adjusting the holders 28 and 30 relative to each other in order that the holders may engage logs of various lengths.

Each holder 28, 30 includes a hollow vertical portion 40 (Fig. 5) that slidably receives a vertical arm 42 having a toothed vertical edge 44. A shaft 46 rotatably supported on portion 40 carries a gear 48 that meshes with the edge 44 to permit vertical adjustment of the arm 42. The forward ends of shafts 46 support discs 50 (Fig. 2) having graduations 52 thereon which will indicate the vertical adjustment of the arms to accommodate logs of various diameters.

The lower ends of the arms 42 rotatably support coaxial horizontal shafts 54 (Figs. 5 and 7) that parallel the rails 10. The adjacent, inner ends of shafts 54 are fixed to plates 56 having outwardly projecting penetrating elements 58 secured thereto. The outer end of one shaft 54 fixedly supports a plate 60 having circumferentially spaced radial slots 62 for selectively receiving a dog 64 pivoted to the corresponding one of the arms 42, in order to retain the shaft 54 in a selected rotated position.

A sawing unit 66 is disposed upon the intermediate support 12 and includes a central horizontal shaft 68 one end of which is operatively connected to a motor 10 (Fig. 6). First and second pairs of spaced parallel circular saw blades 72 and 74 are slidably keyed on shaft 68 for rota-

tion therewith. The carriers 76 and 78 (Fig. 3) for the blades 72 and 74 are fixed to cross bars 80 and 82 (Figs. 1 and 6) having ears 84 and 86 formed at their ends.

A pair of spaced screws 88 and 90 are rotatably supported on the support 12 in parallel relationship with the shaft 68, and the screws are connected by a belt and pulleys 92 for simultaneous rotation. The screws are provided with oppositely threaded end portions that are engaged with complementary threads in the ears 84 and 86, so that as the shafts rotate clockwise the blades 72 and 74 will be moved toward each other, whereas counter-clockwise rotation of the screws will move the blades 72 and 74 away from each other. Spacers 94 are disposed between the blades of each pair of blades and the lengths of the spacers may vary to permit the blades of each pair to be spaced apart a predetermined distance.

A bracket 96 supported on the carriage 14 pivotally supports a pair of vertically swingable gripper arms or tongs 98 (Figs. 2 and 4) whose upper ends are connected by a coil spring 100 that yieldingly urged the lower ends of the tongs 98 apart. Hydraulic means including a cylinder 102 pivotally attached to one of the tongs and a piston rod 104 slidably carried by the cylinder 102 and pivoted to the other of the tongs, constitutes a means whereby the lower ends of the tongs may be moved toward each other to hold side cuts C made in a log L by the blades against the log.

In practical use of the present invention, the carriage 14 is moved on the rails 10 until it clears the sawing unit 66. The valve means is actuated to spread the holders 28 and 30 and then arms 42 are adjusted to the diameter of the log to be cut. The log is held raised by any suitable means and the valve means 38 actuated to move the holders 28 and 30 toward each other and cause the elements 58 to penetrate the ends of the log.

Motor 20 is next started to advance the carriage and motor 70 is also started to drive the saw blades 72, 74, the latter having been previously adjusted for side cut of the log. As the log is fed through the blades, the side cuts C are retained relative to the log by the tongs 98.

After the log has been cut and the carriage passes the saw blades, dog 64 is raised and the log rotated 90° whereupon dog 64 is engaged with another of the notches 62. The motors 20 and 70 are reversed so that the carriage will move back to its original position pulling the log through the blades to provide additional cuts in the log and square the log, after which the valve means 38 is again actuated to release the cut log and its side cuts.

The switch means for the motors and the valve means for the hydraulic members illustrated are all located at a convenient position so that a single operator may regulate the feeding, cutting and releasing of the logs. Obviously, the penetrating members 58 may be engaged with the log before the arms 42 are vertically adjusted to the diameter of the log.

Spacers of various thicknesses are disposed between the blades 72, 74 so as to take care of a board the same thickness as the spacers, thereby sawing a usable board the first time through the saws. The board will not be edged to size; however, when the log is turned ninety degrees, the second cut will produce two boards that will be of the right thickness and which boards will be edged to size. This construction will therefore,

eliminate the necessity of running all four boards through an edger or sizer.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. A sawmill comprising a pair of laterally spaced horizontal rails, a horizontal beam, means riding the rails and supporting the beam at its ends above the rails parallel therewith and between the same and forming with said beam a log carriage movable along said rails, means operatively connected to the carriage to move the same, laterally spaced vertical saw blades, means mounting said blades between said rails beneath said beam for rotation and lateral adjustment to cut different thicknesses off a log, a pair of vertical log holders suspended at upper ends thereof from said beam in depending position for supporting the log at its ends for side cutting by said saws and horizontally slidably on said beam toward and from each other to engage and release the ends of the log, means connecting the holders and operative to slide the same in unison, and means on at least one of said holders for retaining the side cuts alongside the log until the log is released.

2. The combination of claim 1, said holders comprising, respectively, a hollow depending vertical portion, and a vertical log holding arm extending downwardly out of the portion and vertically adjustable slidably therein to raise and lower the log.

3. The combination of claim 1, the third named means comprising a saw driving shaft, carriers for the saws slidable along said shaft, a pair of screw shafts on opposite sides of the saw driving shaft, crossbars mounted on said screw shafts for screw feed thereby and operatively connected to said carriers, and belt and pulley connections between said screw shafts for operation of either by the other.

4. The combination of claim 1, said last named means comprising tongs.

5. The combination of claim 1, said last named means comprising tongs, and pneumatic means on said tongs for closing the same.

ENNO J. DORNATH.
LOUIS R. DETWILER.
